HYDRAULIC STEERING APPARATUS

Frank E. Steinmeyer, Garden City, N. Y., assignor
to Columbian Bronze Corporation, Freeport,
N. Y., a corporation of New York

Application April 5, 1946, Serial No. 659,933

5 Claims. (Cl. 60—52)

1

My invention relates to improved hydraulic apparatus, and particularly to hydraulic steering apparatus. The invention is illustrated particularly in connection with hydraulic steering apparatus for ships.

In known apparatus for this type, it is usual to provide a pump of the reciprocating piston type. This pump is actuated by the rotation of the steering shaft and it actuates a follower piston which operates the rudder. In such known apparatus, it is necessary to move the follower piston synchronously with the pump piston or pistons. Any leakage in the line destroys or lessens this synchronism.

According to my invention, it is not necessary to maintain such synchronism. While the invention is not limited to a pump of the reciprocating piston type or to any type of pump, it is illustrated in connection with this type of pump. Instead of mounting the pump cylinders upon a fixed support as in prior practice, I mount said pump cylinder upon a turnable support which can be turned both clockwise and counter-clockwise, around the axis of rotation of the rotatable steering shaft. The steering shaft actuates the pump piston or pump pistons by a cam or eccentric or by crank and link connections, or any suitable driving means. The flow of liquid out of the pump is controlled by means of controlling valve-means which are fixed to the frame or casing of the apparatus. The position of the rotatable support controls the opening and closing of said controlling valve-means. The turnable support is biased by spring means to a valve-closing position in which said controlling valve-means are closed, so as to prevent the flow of liquid out of the pump cylinders while said support is in said valve-closing position. While the controlling valve-means are thus closed, the torque which is impressed upon the steering shaft by means of the steering wheel, is also impressed upon said turnable support, by means of the pump pistons and pump cylinders, and the pressure of the operating liquid.

Hence, when the steering shaft is turned either clockwise or counterclockwise through a selected small angle, for example, an angle of 5° or less, the turnable support is initially turned in unison with the steering shaft through said selected small angle, until the turning movement of the turnable support opens said controlling valve-means. The further turning of the support is then stopped by a suitable fixed stop. The pump then acts like an ordinary pump which is actuated by the continued rotation of the steering shaft. When the torque on the steering shaft is discontinued and the pressure in the line drops to zero, the turnable support is moved back to its valve-closing position. The steering wheel can thus be turned several revolutions in a se-

2

lected direction, in order to turn the rudder in the selected direction through the desired angle. As soon as the turning of the steering wheel is discontinued, the valve-means are closed, by turning the support back to its valve-closing position, thus locking the rudder in its adjusted position, until the steering wheel is again turned.

Other objects and advantages of my invention are disclosed in the annexed description and drawings.

Fig. 1 is a diagrammatic top plan view, partially in horizontal section. The pump which is illustrated is a two-cylinder pump.

Fig. 2 is a rear vertical elevation of a commercial embodiment, the representation of the rear vertical cover of the casing having been omitted.

Fig. 3 is a top plan view of Fig. 2, partially in horizontal section, taken below the top wall of the casing.

Fig. 4 is a vertical longitudinal section through the line 4—4 of Fig. 2.

The principle of the invention will be explained with reference to Fig. 1.

Eccentric 2 is fixed to the horizontal, rotatable steering shaft 1, so that eccentric 2 and shaft 1 are turned in unison. Shaft 1 has a central axis of rotation 43. The eccentric 2 is the usual cylindrical disc, and it has a horizontal central axis 44. Fig. 1 shows the turnable support 18 in the position in which the controlling valve-means are closed. In Fig. 1, the axis 44 of eccentric 2 is located vertically above axis 43 of steering shaft 1. For convenience, the vertical line 45 and the horizontal line 42 are designated respectively as the major axis and the minor axis of the eccentric 2. The horizontal line 42 intersects the axis 44 of eccentric 2.

In Fig. 1, the pump cylinders 5 and 6 and the pump pistons 3 and 4 are horizontally disposed. Said pump pistons 3 and 4 have outer and planar walls of circular contour, which abut the periphery of eccentric 2 at two horizontal lines which are perpendicular to the plane of Fig. 1, and which are defined by the ends of line 42. The horizontal line 41, which intersects the axis 43 of shaft 1, is coincident with the common lateral axis of cylinders 5 and 6, and pistons 3 and 4. The pistons 3 and 4 are biased towards eccentric 2, so that said pistons always abut the cylindrical periphery of eccentric 2 when the pumping action takes place, by means of compression springs which are located in the cylinders 5 and 6.

The turnable support 18 is yieldingly maintained in its position of Fig. 1, by suitable spring means such as 32—32 shown in Fig. 2.

Pump cylinders 5 and 6 have flexible outlet pipes 7 and 8 which are connected to manifold 16, and flexible inlet or suction pipes 11 and 12, which are connected to a reservoir for the oil or other operating liquid.

Between the cylinders 5, 6 and manifold 16, the flexible outlet pipes 7 and 8 are provided with outlet check-valves which are located in casings 9 and 10, so that the liquid can flow only outwardly through outlet pipes 7 and 8. These casings 9 and 10 are fixed to the frame or casing of the apparatus.

Between the cylinders 5 and 6 and the reservoir, the flexible inlet pipes 11 and 12 are provided with inlet check-valves in casings 14 and 15, so that liquid can flow only inwardly in said pipes 11 and 12. These casings 14 and 15 are also fixed to the frame or casing of the apparatus.

These check-valves are conventional and are not shown. The manifold 16 is also fixed to the frame or casing of the apparatus.

The controlling valve-means are located in a casing 17, which is fixed to the frame or casing of the apparatus. These controlling valve-means can be, for example, an "Electrol" valve which is fully described in U. S. Patent No. 2,349,069 granted May 16, 1944. For this reason, the controlling valve-means are not illustrated.

Manifold 16 is connected to a port of casing 17 by a pipe 16a. The control valves in casing 17 are of the non-leak poppet type.

Respective outlet pipes 25 and 26 are connected to respective ports 25a and 26a of casing 17. Another pipe 24 is connected at one end thereof to a port 24a of casing 17, and at its other end to the same reservoir to which the inlet pipes 11 and 12 are connected.

The poppet valves in valve-casing 17 are actuated and controlled by shaft 23, to which arm 22 is fixed.

When the turnable support 18 and arm 22 are horizontal, all the valves in casing 17 are closed, so that no liquid can flow through pipes 16a, 25, 24, 26. The casing 17 is always filled with liquid.

When arm 22 is turned clockwise from its horizontal position to a downwardly inclined position through an angle of less than 90°, liquid is free to enter valve-casing 17 through pipe 16a, and to pass out of valve-casing 17 only through pipe 26. In such position of arm 22, liquid which enters valve-casing 17 through pipe 25 can flow only through pipe 24 to the reservoir.

When arm 22 is turned counterclockwise through an angle of less than 90° to an upwardly inclined position, liquid can enter valve-casing 17 through pipe 16a, pass out through pipe 25, and the liquid which enters casing 17 through pipe 24 to the reservoir.

Arm 22 is turnably connected by pivot pin 21 to a link 19, which is turnably connected by pivot pin 20 to the turnable support 18.

Pipes 25 and 26 are connected to respective ports 27 and 28 of a fixed cylinder 29. The follower piston 30 is reciprocated between ports 27 and 28. This follower piston 30 actuates the rudder by conventional means, which are not shown. The cylinder 29 is made of sufficient volume between ports 27 and 28, so that it requires a plurality of complete revolutions of the steering shaft 1, to move the follower piston 30 from one extreme position thereof to its other extreme position.

To explain the operation of the device, it is assumed that the steering shaft 1 is turned clockwise, when the parts are in the respective positions of Fig. 1.

When eccentric 2 is turned clockwise, it urges piston 4 inwardly in its cylinder 6, thus producing pressure upon the incompressible liquid in outlet pipe 8, manifold 16 and pipe 16a. This

liquid cannot enter casing 17, because all its valves are then closed. This liquid cannot flow reversely in pipe 7, because of the check-valve in casing 9. The piston 4 is thus, in effect, locked to eccentric 2. The eccentric 2 thus exerts a clockwise torque upon support 18, so that its turns clockwise in unison with eccentric 2. When support 18 is thus turned, the shaft 23 is turned clockwise by arm 22 and link 19.

There may be a slight play between the parts. As soon as arm 22 is thus turned clockwise through a small angle, liquid can flow out of cylinder 6 through pipe 8 through manifold 16, pipe 16a, casing 17, pipe 26, but not through pipes 25 and 24. Pressure is thus exerted upon the follower piston 30, to move it towards port 27, thus turning the rudder in the selected direction. The liquid which is thus pumped out of cylinder 6, must therefore be pumped against the load pressure which is required to actuate the follower piston 30. The force which is exerted by eccentric 2 against piston 4, is applied along a line which is above axis 43, until eccentric 2 has been turned substantially 90° from its position of Fig. 1.

Hence the eccentric 2 will apply a clockwise torque upon support 18, until eccentric 2 has been turned substantially 90° from its position of Fig. 1, making allowance for the small angle in which support 18 is turned in unison with shaft 1.

The turning movement of support 18 around the axis 43 of shaft 1 is stopped by a suitable fixed stop, when support 18 has been turned from its position of Fig. 1 through a selected angle.

For example, this selected angle may be 5° or less. When shaft 1 and eccentric 2 are thus turned clockwise from their positions of Fig. 1, the eccentric 2 will force piston 4 inwardly in a pumping stroke in its cylinder 6, until the line 45 of eccentric 2 is on line 41, while holding support 18 turned clockwise from its position of Fig. 1, against the aforesaid stop. While piston 4 is thus moved in its pressure or pumping stroke, the piston 3 is moved outwardly by its compression spring in its cylinder 5 in a suction stroke.

When eccentric 2 is turned clockwise through 180° from said position in which line 45 is on line 41, to a position in which line 45 is again on line 41, the piston 3 is moved inwardly in its cylinder 5 in a respective pressure or pumping stroke, and piston 4 is moved outwardly by its compression spring in cylinder 6 in a respective suction stroke, while the clockwise torque is maintained upon support 18.

Further clockwise rotation of eccentric 2 during the next quarter revolution, back to the position of Fig. 1, causes outward movement of piston 3 and inward movement of piston 4.

During the pressure or pumping stroke of piston 3, liquid is pumped out of cylinder 5 through its flexible outlet pipe 7, through manifold 16, pipe 16a, casing 17, and to pipe 26, but not through pipes 25 and 24. The follower piston 30 is thus further actuated towards port 27.

Hence the steering shaft 1 can be turned clockwise through several complete revolutions, to reciprocate the pump pistons 3 and 4 in alternate pressure and suction strokes, while supplying liquid under pressure through pipe 26, to actuate the follower piston 30 in the same selected direction.

The same operation is secured when the steering shaft 1 is turned counterclockwise, in which case the support 18 is held tilted counterclock-

wise through the selected angle, until the support 18 abuts another stop.

When the rotation of shaft 1 is stopped, the pressure of the liquid in the respective power line drops to zero.

As an example, it is assumed that the clockwise rotation of the shaft 1 is stopped, when the major axis 45 is in the vertical position of Fig. 1. At this time, the support 18 is slightly tilted clockwise from its horizontal position, preferably through a maximum angle of 5° or less. Immediately prior to the time that transverse line 45 of eccentric 2 again reaches its position of Fig. 1, piston 3 is moving outwardly in its cylinder 5 and is approximately midway in its suction stroke; piston 4 is moving inwardly in cylinder 6 and is approximately midway in its pumping stroke; support 18 is tilted clockwise from its position of Fig. 1, through the aforesaid small angle, and follower piston 30 is moving forwardly towards port 21. At this time, the piston 4 contacts the eccentric 2, along a lateral horizontal line which is in the plane of line 42. The momentum of piston 4 and of the liquid which is then subjected to pressure by piston 4, will move piston 4 slightly away from eccentric 2, when line 45 resumes its position of Fig. 1, and the momentum of piston 3 and the liquid in its suction line will force piston 3 against eccentric 2 at the level of line 42. This will relieve the counterclockwise torque on support 18, so that its spring means, such as the springs 32-32 shown in Fig. 2, will return said support 18 to its normal horizontal position of Fig. 1, thus closing the valves in casing 11, and locking the rudder in its adjusted position.

When the shaft 1 is turned counterclockwise, each pumping stroke of each piston 3 and 4 will force liquid out of casing 17 through pipe 25, but not through pipes 24 and 26.

When the follower piston 30 is moved towards front port 27, the liquid which is in front of piston 30 is forced through pipe 25, and such liquid is by-passed in casing 17 through pipe 24 to the reservoir. Similarly, the liquid which flows through pipe 26 to casing 17 when piston 30 is moved rearwardly, is by-passed through pipe 24 to the reservoir.

If the eccentric 2 is replaced by other driving means for the pump, there is sufficient play in such driving means, or sufficient play in the control valves, to turn the support 18 through the required small angle to horizontal position, when the actuation of shaft 1 is stopped.

As shown in Fig. 3, the practical embodiment of Figs. 2-4 has two eccentrics 2 and 2a. The eccentric 2 operates the pump pistons 3 and 4, and eccentric 2a operates pistons 3a and 4a. The operation is the same as in the embodiment of Fig. 1. These pump pistons have bearing plates B adjacent the eccentrics 2 and 2a.

Fig. 3 shows one of the compression springs S, which urges the respective pump piston outwardly in its respective cylinder in a respective suction stroke against the periphery of the respective eccentric.

The parts are located in a casing 31, which has a removable cover 31a. This casing 31 is filled with oil or other liquid, up to the level of the line L in Fig. 2.

The support 18 is a frame which is turnable around bearings which are coaxial with the axis of shaft 1.

Fig. 2 shows two tension springs 32. Each tension spring 32 has a long U-shaped end 33 which

slidably embraces a respective plate of support 18. Thus, if the support 18 is turned clockwise from its horizontal position of Fig. 2, the left spring 32 will be extended to exert its tension, and the support 18 will slide relative to the slide-end 33 of the right spring 32, thus creating a counter torque which biases support 18 back to its horizontal position.

In the commercial embodiment of Figs. 2-4, one end-portion of support 18 is turnably connected by a pivot pin 20 to a link 35, which is turnably connected by a pivot pin 37 to a lever 60, which is turnably connected to fixed casing 31 by a pivot pin 34. Lever 60 is turnably connected by pivot pin 36 to the link 19, which is normally horizontal in the commercial embodiment, in which the arm 22 is normally vertical. The normally horizontal link 19 is connected by a pivot pin or ball-joint 21 to the normally vertical arm 22.

The cylinders 3 and 3a have respective outlet pipes 7 and 7a and respective inlet pipes 11 and 11a. The check-valve for pipes 7 and 7a are located respectively in casings 9 and 9a. The check-valves for the inlet pipes 11 and 11a are located respectively in casings 14 and 14a.

Fig. 4 shows only a part of pipe 16a. This pipe 16a is connected to port 16b of manifold 16. The outlet check-valve casings such as 9 and 9a, are connected directly to manifold 16, by means of suitable aligned ports.

Pipe 25 is connected to a coupling 25a which is fixed to the bottom wall of casing 31, and pipe 26 is connected to a similar coupling 26a. These couplings are also respectively connected to the respective ports 21 and 28 of the cylinder 29.

Since the parts which are not shown in Figs. 2 and 4 are duplicates of the illustrated parts of Fig. 1, the construction is clear.

As an example, when shaft 1 is turned clockwise as viewed in Fig. 2, the support 18 is turned initially clockwise in unison with shaft 1, thus tensing the left spring 32, while the support 18 slides relative to the U-end 33 of the right spring 32. This provides a reverse or counterclockwise torque upon support 18. The lever 60 is thus turned counterclockwise by link 35, thus actuating link 19 to turn shaft 23 clockwise, until the lower end-portion of lever 60 abuts the wall of casing 31. Since the casing 31 is filled with oil below the line L, the blow of lever 60 against the wall of casing 31 will be cushioned, thus eliminating objectionable noise and vibration. The lever 60 thus acts as a stop for support 18, so that it remains tilted in clockwise position at a small angle, while the clockwise rotation of shaft 1 is continued.

When the shaft 1 is turned counterclockwise, the right spring 32 is tensed, and the support 18 slides relative to the U-end 33 of the left spring 32. Link 35 is now raised to turn lever 60 clockwise, thus turning shaft 23 counterclockwise. The upper end-portion of lever 60 then abuts the wall of casing 31, thus providing the necessary stop. In Fig. 2, the axes of the pivot pins 37 and 34 are in the same horizontal line.

I thus use a single lever 60 for operating the shaft 23 and to function as a stop.

As shown in Fig. 4, the top of casing 31 has a vent cap C, so that the internal pressure of casing 31 is always equal to external atmospheric pressure.

I have described a preferred embodiment of my invention, but numerous changes and omissions and additions can be made without departing

from its scope, and the hydraulic mechanism can be used for any purpose.

The cylinder 29 and the piston 30 which is reciprocated between the ports 27 and 28, represent any kind of servo-motor which is operated by the discharge of liquid from a pressure pump of any type, which is operatively connected to shaft 1. The invention also applies to apparatus in which the shaft 1 is rotated in a single selected direction.

The apparatus can be used for steering vehicles in addition to steering ships.

In the specific embodiment disclosed, the pump-operating means 2 also move the support 18 from its normal position in Fig. 1 to a position in which said support 18 also holds the controlling valve-means in casing 17, in respective open and closed positions, but the invention is not limited to this dual function of said pump-operating means.

While I have illustrated a pressure hydraulic pump, the invention is not limited thereto, and it is not necessarily limited to the use of a hydraulic system, because the operating fluid may be air or a gas, in any type of power transmission.

The cylinder 29 and piston 30 exemplify a reversible servo-motor which may be of any type and which has respective ports, as exemplified by ports 27 and 28, through which the operating fluid can enter said servo-motor and pass out of said servo-motor. The direction of movement of said servo-motor depends upon the direction of movement of the operating fluid in said servo-motor between said ports. The controlling valve-means are adapted to connect either of said ports to said pump. These controlling valve-means are connected in any manner to the shaft, so that when the shaft is turned in one direction, one of said ports remains connected to said pump, and when the shaft is turned in the reverse direction, the other port remains connected to said pump, while the shaft is turned through any desired angle. Optionally, said controlling valve-means are biased so as to close both said ports when the shaft is stationary.

The ports by which pipes 25, 24, 26 are respectively connected to casing 17, are respectively designated as 25a, 24a, 26a. The legend adjacent Fig. 1 sufficiently designates the operation of the controlling valve-means in casing 17, since the same are well-known per se.

I claim:

1. Hydraulic apparatus which comprises a rotatable shaft, a pump operatively connected to said shaft by pump-operating means and operated by the rotation of said shaft to discharge liquid from said pump, a servo-motor connected to said pump by connecting pipe-means, said servo-motor being operated by the liquid which is discharged from said pump through said pipe-means, movable controlling valve-means located in said pipe-means between said pump and said servo-motor, said controlling valve-means being movable to a closing position to prevent the flow of liquid through said pipe-means from said pump to said servo-motor, said controlling valve-means being also movable to an open position to permit said flow of liquid, said pump being fixed to a movable support, said support being connected to said controlling valve-means by connecting means to operate said controlling valve-means to either of said positions, said support being biased by biasing means to a normal position in which said support holds said controlling valve-means in said closing position, said shaft

having means to move said support from said normal position to a position in which said support holds said controlling valve-means in said open position only during the period in which said shaft is rotated and the liquid in said pump is under pressure, said biasing means being operative to move said support back to said normal position when the rotation of said shaft is discontinued.

2. Hydraulic apparatus which comprises a rotatable shaft, a pump operatively connected to said shaft by pump-operating means and operated by the rotation of said shaft in either direction to discharge liquid from said pump, a servo-motor which has two sides and which is operable in two opposite directions, said servo-motor being connected to said pump by connecting pipe means which are connected to the two opposite sides of said servo-motor, said servo-motor being operated by the liquid which is discharged from said pump through said pipe-means, movable controlling valve-means located in said pipe-means between said pump and said servo-motor, said controlling valve-means being movable to respective closing and opening positions to respectively prevent and permit the flow of liquid from said pump to said servo-motor and to direct the flow of said liquid into either of the two sides of said servo-motor, thereby controlling the direction of operation thereof, said pump being fixed to a support which is turnable around the axis of said shaft, stop-means for limiting the turning movement of said support in respective opposed directions, said support being connected to said controlling valve-means by connecting means to operate said controlling valve-means to either of said positions, said turnable support being biased by biasing means to a normal position in which said support holds said controlling valve-means in said closing position, said pump-operating means being constructed and operative to turn said support in unison with said shaft until the turning movement of said support is stopped by said stop-means, said pump-operating means being constructed and operative to continue to operate said pump upon continued rotation of said shaft after said turning movement of said support has been stopped, said support holding said controlling valve-means open in a respective selected opening position and directing the flow of liquid into a selected side of the servo-motor to operate said servo-motor by said pump in a selected direction by the continued rotation of said shaft when said support abuts said stop-means, the pipe-means which are connected to a respective end of said servo-motor temporarily acting as an inlet for said servo-motor when it is operated in one direction and temporarily acting as an outlet for said servo-motor when it is operated in the opposed direction, said controlling valve-means being connected through an open port to an exhaust for said servo-motor and connecting to said exhaust the pipe-means which are temporarily acting as an outlet, when said support abuts said stop-means.

3. Hydraulic apparatus which comprises a rotatable shaft which is rotatable in respective opposed directions, an eccentric fixed to said shaft, a support which is turnable around the axis of said shaft in respective opposed directions, said pump comprising at least two aligned cylinders and pump pistons movable to-and-fro in said cylinders, said pistons having a common

piston-axis which intersects and is lateral to the shaft-axis, said shaft and said eccentric being located between said pistons, each said cylinder having an inlet pipe which is connected through an inlet check-valve to a reservoir, each said cylinder having an outlet pipe which is connected through an outlet check-valve to a casing in which controlling valve-means are located, said controlling valve-means being operated by a valve-shaft, said valve-shaft being connected to said turnable support, a servo-motor which comprises a servo-cylinder which has longitudinally spaced ports and a servo-piston which is slideable in said servo-cylinder between said ports, a first servo-pipe which connects said casing to one of said ports, a second servo-pipe which connects said casing to the other of said ports, a third pipe connected at one end to said casing and connected at its other end to said reservoir, said controlling valve-means being movable (a) to a position in which said casing is closed; (b) to respective positions in each of which liquid can enter said casing through a selected outlet-pipe and liquid can flow out of said casing through a selected servo-pipe and liquid can enter said casing through the other servo-pipe to be by-passed to said reservoir through said third pipe; said support being biased by biasing means to a normal position in which it holds said controlling valve-means in said position (a); said support holding said controlling valve-means in said position (b) when said support abuts said stop-means.

4. Hydraulic steering apparatus comprising a steering shaft, an eccentric mounted on said shaft, a pair of cylinders on diametrically opposite sides of said eccentric, fluid in said cylinders, a pair of pistons in said cylinders in operative engagement with said eccentric whereby rotation of the steering shaft and of the eccentric mounted thereon causes reciprocating movement of the pistons, said piston cylinders being mounted on a pivotable support whose pivot coincides with the longitudinal axis of the steering shaft, stop members which limit the pivotal movement of said pivotally mounted support, tension means connected to said pivotally mounted support and normally urging said support into a neutral position, the torque action of said steering shaft upon said pivotal support through the pistons which the eccentric on said shaft engages being such as to cause pivotal movement of the pivotal support against the action of the tension means and in the direction in which the steering shaft is turned, such pivotal movement ceasing when the pivotal support engages a stop member, further turning movement of the steering shaft causing axial movement of the pistons without affecting the angular position of the pivotal support, a valve, fluid in said valve, pipelines connecting the two cylinders with said valve, a fluid operated servo-motor which has two sides and which is operable in opposite directions, pipelines connecting said valve to the two sides of said servo-motor and valve controlling means connected to said pivotal support whereby pivotal movement of said support operates said valve and opens and closes the pipelines to the respective sides of the servo-motor, whereby the servo-motor is caused to operate in one direction when the flow of liquid under pressure is admitted by the valve into one side of said servo-motor and whereby the servo-motor is caused to operate in the opposite direction when

10
the flow of liquid is directed into the opposite side thereof by said valve, each pipeline operating temporarily as an inlet for said servo-motor when it is operated in one direction and operating temporarily as an outlet for said servo-motor when it is operated in the opposite direction, an exhaust for said servo-motor, said valve being actuated to connect the pipeline which is temporarily acting as an outlet to said exhaust when said pivot support engages a stop member.

5. Hydraulic steering apparatus comprising a steering column, a rotatable support mounted on said steering column, said support being co-axial with said steering column, tensioning means connected to said rotatable support and tending to hold said support in neutral position, stop members adjacent said support which limit the angular movement of said support, a pair of diametrically opposed cylinders mounted on said support, pistons and liquid under pressure in said cylinders, and an eccentric fixedly mounted on said steering column and operatively engaging said pistons, whereby rotary movement of said steering column provides a torque action upon the support through said eccentric, said pistons and said liquid under pressure, causing pivotal movement of said support in the direction of rotation of said steering column against the action of the tension means connected thereto, said pivotal movement of the support ending when the support is brought into contact with one of the stop members, further rotary movement of the steering column causing actuation of said pistons in their respective cylinders, pipelines connected to said cylinders, a valve connected to said pipelines, a source of liquid under pressure connected to said valve, additional pipelines connected to said valve and a fluid operated servo-motor connected to said additional pipelines, said servo-motor being operable in two opposite directions and having two sides to receive said liquid under pressure through said additional pipelines, said valve being connected with a controlling member which is operatively connected to the rotatable support, whereby angular movement of said support in response to rotation of the steering column causes the valve to open and close to direct the flow of liquid under pressure through the additional pipelines into either side of the servo-motor, thereby causing said servo-motor to operate in a selected direction, each pipeline operating temporarily as an inlet for said servo-motor when it is operated in one direction and operating temporarily as an outlet for said servo-motor when it is operated in the opposite direction, an exhaust for said servo-motor, said valve being actuated to connect the pipeline which is temporarily acting as an outlet to said exhaust when said pivot support engages a stop member.
